COIN TUBE AND OPENER THEREFOR

Gerald A. Hale, Oklahoma City, Okla., assignor
to Magee-Hale Park-O-Meter Company, Oklahoma City, Okla., a corporation of Delaware

Application January 12, 1951, Serial No. 205,665

11 Claims. (Cl. 232—16)

1

This invention relates to improvements in means for collecting coins from coin operated devices such as parking meters and the like, and more particularly, but not by way of limitation, to an improved coin receptacle and opener therefor.

As is well known, in municipalities utilizing parking meters, the safe and efficient collection of coins is an important step in the operation of an efficient parking system. Heretofore a majority of the parking meters in operation were provided with a sealed coin box which was replaced periodically with an empty coin box by a coin collecting operator. The operator returned the filled or partially filled coin boxes to the office where the boxes were opened and the coins counted by another employee of the municipality. Although this is a relatively safe method of collecting coins from parking meters, it will be readily appreciated that a large amount of office work is required to seal and store the numerous coin boxes and a substantial number of man hours is required to exchange the boxes at the meters.

Another method of collecting coins is to provide the collecting operator with a collecting receptacle. In this method the operator opens a coin retaining box attached to each meter and bodily removes the coins from the meter into the collecting receptacle. The collecting receptacle is subsequently returned to the office where the collected coins are counted. It will be observed, of course, that the coins may be collected in a relatively short period of time and the office work is reduced to a minimum, however, the collecting operator comes into direct contact with the coins and the municipality may lose a portion of its revenue.

This invention contemplates a combining of the beneficial results of the above described methods and an elimination of the unsatisfactory results obtained by each method. To accomplish these results, I contemplate a novel coin receptacle or tube for a parking meter which cannot be unauthorizedly opened. A spring loaded plunger is provided in the coin tube that may be removed from the tube to remove coins therefrom only by use of a special tool. A collecting device is provided in the form of a collector receptacle having a novel tool therein for opening the coin tubes at the various meters. The collecting operator transports the collecting device to the various meters on a suitable cart and the coin tube at each meter is removed from the meter and inserted in the collecting device. The opening tool is then actuated by the operator to open the coin tube and transfer the coins from the coin tube into the collecting device. The coin tube is automatically closed upon release of the opening tool and the opening

2

tool cannot be removed from the collecting device without detection. Furthermore, the collected coins cannot be removed from the collecting device without detection, and the operator does not come into direct contact with the coins.

An important object of this invention is to provide safe and efficient means for collecting coins from parking meters.

Another object of this invention is to preclude the collecting operator from coming into contact with the coins while collecting the coins from a parking meter.

A further object of this invention is to provide a novel coin tube and opener therefor.

Another object of this invention is to reduce to a minimum the office work involved in collecting coins from parking meters.

Another object of this invention is to provide a practical and efficient coin tube and opener therefor.

A still further object of this invention is to provide an economical coin tube and opener therefor having a long service life.

Other objects and advantages of the invention will be evident from the following detailed description, read in conjunction with the accompanying drawings, which illustrate my invention.

In the drawings:

Figure 1 is a perspective view of a novel coin collector having a coin tube disposed therein.

Figure 2 is a vertical sectional view of the coin tube.

Figure 3 is a vertical sectional view of the collector.

Figure 4 is a sectional view of a portion of the collector and coin tube illustrating the position of the mechanism immediately prior to the opening of the coin tube.

Figure 5 is a view similar to Figure 4 taken at right angles to Figure 4 and illustrating the position of the mechanism when the coin tube is in an open position.

Referring to the drawings in detail, and particularly to Fig. 1, reference character 2 generally designates a novel coin collecting device comprising a cylindrical housing 4. A door 6 is provided in the top 8 of the housing 4 and may be locked in any suitable manner (not shown). The collecting device 2 is transported to the various parking meters (not shown) by a suitable cart (not shown) in the usual manner. A tubular stack or pipe 10 is secured in the housing 4 and extends through the upper end 8 thereof to receive a novel coin tube generally indicated at 12.

The coin tube 12 (see also Fig. 2) is normally disposed in a parking meter (not shown) or other coin operated devices (not shown) to receive the coins inserted therein in the usual manner, and comprises a tubular housing 14 hav-

ing a head 16 rigidly secured in the upper end thereof. A circumferential flange 18 is provided on the outer periphery of the head 16 and extends outwardly beyond the outer periphery of the housing 14 for purposes as will be herein-after set forth. A rectangular shaped opening 20 is provided in the head 16 to receive a pair of flippers 22. Transverse arms (not shown) are provided on the upper end of each flipper 22 and extend into complementary slots 26 in the head 16. The flipper arms are pivotally retained in the slots 26 by a suitable apertured retaining plate 28 secured to the head 16 by drive screws 30. The lower ends 32 of the flippers 22 are normally in contact as shown in Fig. 2 to close the opening 20. An obliquely extending arm 34 is provided on each flipper 22 and is engaged by a downwardly extending hook 36. The hooks 36 are in turn connected to the upper end of a helical tension spring 38 extending through the housing 14.

It will be readily apparent that the spring 38 acts through the medium of the hooks 36 and arms 34 to retain the flippers 22 in a closed position. When a coin (not shown) is forced between the flippers 20, the spring 38 is stretched to permit passing of the coin into the housing 14. The flippers 22 and opening 20 are preferably essentially the same length as the diameter of the largest coin to be inserted in the housing 14, thereby precluding an unauthorized opening of the flippers 22 by a screw driver or the like (not shown) to remove coins from the coin tube 12.

A plunger 40 is provided in the lower end of the housing 14 and is connected to the lower end of the tension spring 38. Suitable stops 41 (see Fig. 5) are provided in the lower portion of the housing 14 to limit the movement of the plunger 40 into the housing 14. The upper surface 42 of the plunger 40 (Figs. 2 and 5) is curved for purposes as will be herein-after set forth. A large tapered aperture 43 is provided concentrically in the lower surface 44 of the plunger 40 and communicates with a smaller concentric bore 45. A pair of diametrically opposed aligning apertures 46 are also provided in the lower portion of the plunger 40 in communication with the lower face 44 thereof.

It will be readily apparent that the tension spring 38 will retain the plunger 40 in the housing 14 against the stops 41 to close off the lower end thereof as well as retain the flippers 22 in a closed position. It will also be readily seen that the plunger 40 cannot be pulled out of the housing 14 against the action of the spring 38 by an ordinary wrench or the like (not shown) to open the coin tube 12.

To remove the plunger 40 from the housing 14, I provide an opener indicated generally at 47 (Fig. 3) and disposed in the stack 10 within the container 4. The opener 47 comprises a vertically disposed rod or shaft 48 extending partially through the stack 10. A tapered head 49 is rigidly secured on the upper end of the rod 48. The upper end 50 of the head 49 is cylindrical in configuration and is adapted to enter the bore or recess 45 of the coin tube plunger 40 as will be herein-after set forth. The tapered portion 51 of the head 49 is tapered upwardly and outwardly at a slightly greater angle from the vertical than the tapered bore 43 of the coin tube plunger 40. A spring 52, herein-after termed a "garter" spring, is disposed circumferentially around the tapered head 49. The spring 52 is formed by simply interconnecting the opposite ends of a suitable

helical tension spring. Furthermore, the garter spring 52 is placed on the head 49 under tension, therefore, the spring 52 constantly tends to crawl downwardly over the tapered portion 51 of the head 49.

An apertured cylindrically shaped actuator 53 is reciprocally disposed on the rod 48 below the head 49. A pair of opposed transverse pins 54 are secured in the lower end of the actuator 53 and extend into complementary slots 55 provided in the stack 10. The pins 54 and slots 55 limit the reciprocatory movement of the actuator 53 as will be more fully herein-after set forth. A cylindrical recess 56 is provided in the upper end of the actuator 53 to receive the tapered head 49. An upstanding circumferential flange 57 surrounds the recess 56 and is adapted to contact the garter spring 52 to control the movement thereof. A pair of vertically disposed pins 58 (see Fig. 5) are also carried in the upper end of the actuator 53 and are adapted to be disposed in the aligning apertures 46 of the coin tube plunger 40.

An enlarged cylindrical recess 59 (Fig. 3) is provided in the lower portion of the actuator 53 to receive a helical compression spring 60 surrounding the rod 48. The upper end of the spring 60 is anchored to the actuator 53 and the lower end thereof is anchored to a collar 61 rigidly secured on the rod 48. It will be readily apparent that the spring 60 constantly tends to retain the actuator 53 in its uppermost position with the pins 54 in the upper ends of the slots 55.

Openings 62 (see Fig. 5) are provided in the opposite sides of the stack 10 adjacent the top 8 of the container 4 to provide an entrance for coins (not shown) into the container 4. A sleeve 63 is slidingly disposed over the stack 10 to cover the openings 62 when the container 4 is inverted to preclude an unauthorized removal of coins from the container 4. When the container 4 is in an upright position, as shown, the sleeve 63 is disposed below the opening 62 and rests on a drive screw 64 provided in the stack 10.

Another collar 65 (Fig. 3) is secured on the shaft 48 below the collar 61 to anchor the upper end of another helical compression spring 66 surrounding the shaft 48. The lower end of the spring 66 is anchored to an apertured plug 67 rigidly secured in the stack 10 by screws 68. The spring 66 is stronger than the spring 60 for purposes as will be herein-after set forth. The shaft 48 extends through the plug 67 and has an extension 69 secured on the lower end thereof, in turn extending below the lower end 70 of the stack 10. A plunger 71 is secured on the shaft 48 adjacent the extension 69 and below plug 67. The plunger 71 compresses air in the stack 10 between the plunger 71 and plug 67 upon an upward movement of the shaft 48, thereby cushioning the final upward movement of the shaft. An escape port 72 is provided in the stack 10 below the plug 67 to permit free movement of the plunger 71 during a portion of its upward movement.

A lever 73 is pinned to the lower end of the shaft extension 69. The lever 73 is pivotally secured at one end by a pin 74 to a yoke member 75 in turn secured to the raised bottom 76 of the container 4. An elongated slot 77 is provided in the lever 73 to receive the pin 74, thereby permitting true vertical movement of the shaft 48 and extension 69 upon actuation of the lever 73. The lever 73 extends through a vertical slot 78 provided in the container 4 and has a foot pedal 79 secured on the outer end thereof. A flange 80

is provided on the lower end 70 of the stack 10, and the flange 80 is in turn secured to the bottom 76 of the container 4 by a plurality of bolts 82. The bolts 82 are held by nuts 84 welded to the bottom 76. A lead seal (not shown) may interconnect the bolts 82 to prevent an unauthorized removal of the stack 10 if desired. The lower end 86 of the container 4 is preferably provided with a reinforcing ring 88.

Operation

In operation, the collecting device 2 is transported to the various parking meters (not shown) on a suitable cart (not shown) by the collecting operator. At each parking meter, the coin tube 12 is removed therefrom and inserted in the stack 10 as shown in Figs. 1 and 4. The coin tube 12 is then turned until the aligning apertures 46 (Fig. 5) are aligned with the pins 58, permitting downward movement of the coin tube 12 until the upper end 50 of the head 49 completely enters the recess 45 of the plunger 40. The garter spring 52 will then be retained by the actuator flange 57 in such a position that the center line of the garter spring 52 is essentially even with the lower face 44 of the plunger 40.

The lever 73 is then moved downwardly by the pedal 79 to open the coin tube 12. During the initial downward movement of the shaft 48 and head 49, the spring 60 will retain the actuator 53 in its uppermost position as shown in Fig. 4 to retain the garter spring 52 in its upper position. The head 49 will therefore be moved down in the spring 52 to expand the spring. Also during the initial downward movement of the head 49, the entire coin tube 12 moves down simultaneous with the head 49 until the circumferential flange 18 of the coin tube head 16 contacts the upper end of the stack 10. Since the degree of taper of the head 49 is greater than the degree of taper of the recess 43, the garter spring 52 will become wedged between the head 49 and walls of the recess 43 when the head 49 and plunger 40 have moved downwardly a predetermined distance over the spring 52. The garter spring 52, will, of course, become wedged between the head 49 and plunger 40 to interlock the head and plunger slightly before, or simultaneous with, the contact of the circumferential flange 18 and stack 10.

Upon contact of the flange 18 and stack 10, and continued downward movement of the head 49, the plunger 40 will be moved downwardly out of the housing 14 through the medium of the garter spring 52 to the position shown in Fig. 5. The garter spring 52 is retained in a wedged position between the head 49 and plunger 40 by the actuator flange 57 through the action of the spring 60. When the garter spring 52 has become wedged as set forth, the actuator 53 is moved downward simultaneous with the head 49 and plunger 40.

As the plunger 40 is removed from the housing 14, coins (not shown) will fall by gravity out of the housing 14 and through the openings 62 into the container 4. It will be noted that the slanting portions of the plunger upper surface 42 are aligned with the openings 62 to facilitate removal of the coins. Furthermore, the entire surface 42 is curved, thereby minimizing the tendency of coins to adhere to the plunger 40 by reducing the contact area between the falling coins and the plunger.

Upon removal of the coins from the coin tube 12, the pedal 79 is released, permitting the combined action of the springs 38 and 66 to move the head 49, plunger 40 and actuator 53 simultane-

ously upward. During the final upward movement of the head 49, the pins 54 (Fig. 4) contact the upper ends of the slots 55 to stop the actuator 53. It will be noted that the spring 66 is stronger than the spring 60, and will, therefore, force the head 49 upward against the action of the spring 60 after the actuator 53 has been stopped. The garter spring 52 will thereby be released and permitted to crawl downwardly over the head 49 to release the plunger 40. The spring 38 will then move the plunger 40 back into the lower portion of the housing 14 against the stops 41, whereupon the coin tube 12 may be removed from the stack 10 and reinserted in a parking meter.

After a plurality of coin tubes 12 have been emptied into the container 4, the collecting device 2 is returned to the office where the coins are counted by office personnel.

From the foregoing it is apparent that the present invention provides safe and efficient means for collecting coins from a parking meter. The collecting operator does not come into direct contact with the coins, and the office work is reduced to a minimum. It is also apparent that the present invention provides a practical and efficient coin tube and opener therefor which may be economically manufactured.

Changes may be made in the combination and arrangement of parts as heretofore set forth in the specification and shown in the drawings, it being understood that any modification in the precise embodiment of the invention may be made within the scope of the following claims without departing from the spirit of the invention.

I claim:

1. In a coin collecting apparatus, comprising a coin tube, a spring loaded plunger in one end of the tube having a recess therein, and an opener for the coin tube, said opener comprising a head of a size to enter the recess, and expandable means carried by the head to engage the walls of said recess whereby the plunger may be removed from the coin tube upon movement of said head to remove coins from the tube.
2. In an apparatus of the character described, comprising a coin tube, a plunger in one end of the coin tube, one end face of said plunger being exposed and having a tapered recess therein, and an opener for the coin tube, said opener comprising, a tapered head of a size to enter the tapered recess, and expandable means carried by the tapered head for interlocking the head to the walls of the recess in one position thereof, whereby the plunger may be removed from the coin tube to remove coins therefrom, and means for actuating the expandable means.
3. In apparatus of the character described, comprising a coin tube, a plunger in one end of the coin tube, one end face of said plunger being exposed and having a tapered recess therein, and an opener for the coin tube, said opener comprising, a tapered head of a size to enter said recess, a garter spring on the tapered head for interlocking the head to the walls of the recess in one position thereof, and means for moving the garter spring into locking position.
4. In apparatus of the character described, comprising a coin tube, a removable plunger in the coin tube, a spring in the tube for retaining the plunger therein, one end face of said plunger being exposed and having a tapered recess therein, opener means for removing the plunger from the tube, said opener comprising a shaft, a tapered head on one end of the shaft of a size to enter said tapered recess, a garter spring on

the head for interlocking the head to the walls of the tapered recess in one position thereof, and an actuator on the shaft for moving the garter spring into locking position.

5. In apparatus of the character described, comprising a portable container, a stack extending into the container, a coin tube insertable in the stack, stop means for limiting the movement of the coin tube in the stack, a removable plunger in the innermost end of the coin tube, a lever extending from the container, and opening means in the container actuated by the lever for removing the plunger from the coin tube.

6. In apparatus of the character described, comprising a portable container, a stack extending into the container, a coin tube insertable in the stack, stop means to limit the movement of the tube in the stack, a plunger in the tube, a spring in the tube for retaining the plunger therein, one end face of the plunger being accessible through the lower end of the tube, a recess in said one end face of the plunger, a movable shaft in the container below the coin tube, expandable means carried by the shaft for engaging the walls of said recess, a lever extending from the container for moving the shaft and removing the plunger from the coin tube, whereby coins will fall from the coin tube into the container.

7. In apparatus of the character described, comprising a coin tube, a removable plunger in the coin tube, a spring for normally retaining the plunger in the coin tube, one end face of the plunger being exposed, a recess in said one end face of the plunger, a portable container for receiving collected coins, a stack extending from the container to receive the coin tube in such a manner that the exposed face of said plunger will face the container, stop means for limiting the movement of the coin tube in the stack, a reciprocable shaft in the container, a head on the shaft insertable in said recess, locking means carried by the head to lock the head in the plunger in one position thereof, a lever for moving the shaft and head to remove the plunger from the coin tube, and spring loaded actuating means for automatically moving said locking means into said one position during the initial opening movement of the shaft and head.

8. In apparatus of the character described, comprising a coin tube, a removable plunger in the coin tube, a spring for normally retaining the plunger in the coin tube, one end face of the plunger being exposed, a recess in said one end face of the plunger, a portable container for receiving collected coins, a stack extending from the container to receive the coin tube in such a manner that the exposed face of said plunger will face the container, stops means for limiting the movement of the coin tube in the stack, a reciprocable shaft in the container, a tapered head on the shaft insertable in said recess, a garter spring on the head for interlocking the head to the walls of the recess in one position thereof, an actuator reciprocably disposed on the shaft for moving the garter spring into said one position, said garter spring being disposed on the tapered head under tension whereby said spring moves into an unlocking position when released by the actuator, means for controlling the movement of the actuator, and a lever for moving the shaft.

9. In apparatus of the character described, comprising a portable container, a vertical stack extending into the container, opposed openings in the stack communicating with the interior of

the container adjacent the upper end thereof, a coin tube insertable in the stack, stop means for limiting the movement of the coin tube in the stack, a plunger in the lower end of the coin tube, a spring for normally retaining the plunger in the coin tube, a recess in the lower face of the plunger, the upper surface of the plunger being essentially an inverted V-shape to provide opposed slanting surfaces, opening means in the container for engaging the walls of the recess and removing the plunger from the coin tube, a lever extending from the container for actuating the opening means, and means for aligning the slanting surfaces of the plunger with the opposed openings in the stack to direct coins from the coin tube into the container upon removal of the plunger.

10. In apparatus of the character described, comprising a portable container, a vertical stack extending into the container, opposed openings in the stack communicating with the interior of the container adjacent the upper end thereof, a coin tube insertable in the stack, stop means for limiting the movement of the coin tube in the stack, a plunger in the lower end of the coin tube, a spring for normally retaining the plunger in the coin tube, a recess in the lower face of the plunger, the upper surface of the plunger being essentially an inverted V-shape to provide opposed slanting surfaces, said slanting surfaces being curved to provide the minimum contact for coins resting thereon, opening means in the container for engaging the walls of the recess and removing the plunger from the coin tube, a lever extending from the container for actuating the opening means, and means for aligning the slanting surfaces of the plunger with the opposed openings in the stack to direct coins from the coin tube into the container upon removal of the plunger.

11. In apparatus of the character described, comprising a portable container, a vertical stack extending into the container, opposed openings in the stack communicating with the interior of the container adjacent the upper end thereof, the lower end of said stack being sealed from the interior of the container, a coin tube insertable in the stack, stop means for limiting the movement of the coin tube in the stack, a plunger in the lower end of the coin tube, a recess in the lower face of the plunger, the upper surface of the plunger being essentially an inverted V-shape to provide opposed slanting surfaces, opening means in the container for engaging the walls of the recess and removing the plunger from the coin tube, a lever extending from the container for actuating the opening means, means for aligning the slanting surfaces of the plunger with the opposed openings in the stack to direct coins from the coin tube into the container upon removal of the plunger, and a reciprocable sleeve on the stack within the container to cover the openings upon inversion of the container to preclude removal of coins from the container through the stack.
